Steel Patent

Whereas I, James Mc Elroy, have, during part of the
same containing a description of the same, the said James Mc Elroy has
made, of his improvement in the Lock for Bank Notes, known and for
all the purpose.

I call to witness that I have had the same to be known
that I, James Mc Elroy of the City, County and State of New York, have
invented a new and useful improvement in the Lock for Bank Notes
knows me and that the following is a full true and exact description, the
of which taken in connection with the drawing, which this specification
refers, the Stock or Case or made similar to that of the common door
lock.

Within the case is placed a set of guards, represented at A
each guard having a slot at each end thereof, working con permanent
Stock. In the upper edge of each guard, is a notch to receive the Check
it must be described. The notches are made at different distances from
the end of the guard, the in making the lock the notches cannot be made
until the peculiar form of the key is determined. Between these pair
of guards is placed a projection at each end to enable the guards to
strike independently of each other.

These guards are thrown horizontally back
and forward by the key, it having a bit consisting of steps or rises & steps
of different lengths corresponding to the notches in which
they act. The Check or turning vertically in a slot in the plate lies
upon its upper edge a projection which rises into a notch in the
end of the smaller side of the bolt, and on the outer side of the check
is a projection which drops into the notches in the guards, to keep
them from being turned by the proper key. The letter D.D. is for the purpose of de-
scribing the outside knob, it works on a permanent stock of iron
and in the outside is a notch which is intended to secure the

the followers E. E. to which has been attached. This is that part of the Check (but at a right angle with the part C) having a small stamp R. in it which extracts the bolt out of the lock. It is such a mechanism that when the Check is permitted to turn the notches in the guards by the action of the key the bolt is sprung. Carrying the stamp R. raises the lever Q. of the follower E and gives liberty to the notches back to be acted upon. The key M. is inserted to lock and unlock the bolt. This is done by acting upon the guard, and placing them in their proper position to receive the Check which is thrown into them by a spring. It then acts upon the bolt and puts it in a locked or unlocked position and secures it by replacing the guards. This is done by the key striking a pin on the opposite side of the square and moving the guards back in a bodily.

The night key M. No 2 is similar to the other except that two of the stops are taken off so that it will not act upon the bolt. This night key has an advantage over all others in the circumstance that it is as difficult to counteract it as the main key since it acts in the same key hole and upon the same guards. By the use of this key fine door locks are rendered perfectly safe during the time the bolt is withdrawn as the notches back cannot be turned until all the guards are bolted into their proper position. It is a exp to secure the upper follower E in its proper place. It is a exp which is placed over the work of the lock. D. and E are the pieces of tie placed between the guards that they may work independently of each other. G. G. are the levers by which the key is enabled to unlock the bolt.

That I claim as my own invention and not previously known or used in the above described lock. D. Firstly are the pins inserted upon the guards before the made by which the hardened levers (described in my Patent of the 19th March 1836) are suspended with. These guards have a cavity cut into them all around to receive the key to pass through the bolt. Secondly in forming the notches in the bolt. Once it and again draw it. I claim secondly the application of this principle to the night latch for front door
